UNITED STATES PATENT OFFICE.

STEPHEN HUACK, OF DANNEMORA, NEW YORK.

BLOTTER.

1,303,902.

Specification of Letters Patent. Patented May 20, 1919.

Application filed October 4, 1918. Serial No. 256,857.

To all whom it may concern:

Be it known that I, STEPHEN HUACK, a citizen of the United States, residing at Dannemora, in the county of Clinton, State 5 of New York, have invented a new and useful Blotter; and I do hereby declare the following to be a full, clear, and exact description of the invention, such as will enable others skilled in the art to which it appertains to make and use the same.

This invention relates to an improved construction of blotter, and an object of the invention is to provide a device of this kind particularly adapted to be worn on the hand 15 while writing, and when so worn will permit clerks and book-keepers and the like to turn leaves of books, ledgers and the like, thereby avoiding the delay of laying the blotter down, and again picking it up when 20 needed. Further, a blotter so worn on the hand will not interfere with lifting or carrying books or ledgers from one desk to another, or to the book racks.

It is obvious that a blotter of this kind 25 is at all times conveniently at hand, so that after each and every line or a section thereof, the writing may be easily blotted, by simply moving the hand forwardly and placing the blotter over the line that has been written.

30 A further object of the invention is to provide an improved fastening means for securing the blotter to the hand.

A further object of the invention is to 35 provide a fastening means comprising long and short extension strips on the longitudinal side edges of the blotter and integral therewith, and to be overlapped on the back of the hand, in combination with a loop for holding the strips overlapped, there being 40 lateral parts cooperating with the loop to prevent a sliding separation of the strips.

In practical fields the details of construction may necessitate alterations falling within the scope of what is claimed.

45 The invention comprises further features and combination of parts as hereinafter set forth, shown in the drawings, and claimed.

In the drawings:—

Figure 1 is a view in perspective of the 50 improved blotter constructed in accordance with the invention and illustrated as applied to a hand, for use.

Fig. 2 is a plan view of a hand, showing the blotter fastened thereto.

55 Fig. 3 is a plan view of the blotter con-

structed in such a manner that the same may be stamped or cut from a blank.

Fig. 4 is a detail sectional view on line 4—4 of Fig. 2.

In constructing a blotter, a piece of blotting paper may be provided as a blank, from which the blotter 1 as shown in Figs. 1, 2 and 3, may be stamped or cut. The blotter proper may be any suitable shape, preferably as shown, for instance elongated and 60 having its forward and rear edges curved as shown at 2 and 3. In cutting the blotter from a blank, extension strips, long and short are formed integral with the longitudinal side edges of the body 1 of the blotter, 70 adjacent the rear end edge 3 thereof. These extension strips 4 and 5 have their end portions terminating in transverse parts 6 and 7, which extend laterally beyond the edges of the strips 4 and 5. These extension strips 75 4 and 5 may be made in different lengths, whereby blotters may be constructed to fit hands of different sizes. Preferably the extension strips are designed to overlie the back of the hand, slightly to the rear of the 80 knuckle, as shown clearly in Figs. 1 and 2. However, the extension strips may be made short enough to overlie the second, third and little fingers, or to overlie the third and little fingers. However, in these cases the body 85 of the blotter may be made slightly shorter, than when the strips overlie the back of the hand. In fastening the blotter to the hand the extension strips are overlapped, as in Figs. 1 and 2, the strip 5 overlapping the 90 strip 4, and in suchwise that the transverse parts 6 and 7 may be spaced as shown in Figs. 1 and 2. To hold the extension strips overlapped, a loop 8 to be constructed of any suitable material preferably blotting paper 95 or ordinary paper is provided. This loop is constructed from an elongated strip, folded upon itself as shown at 9, so that its ends may be overlapped and secured together by any suitable adhesive material. However in 100 forming the loop, the strip is passed under the underlapped extension strip 4 and over the overlapped extension strip 5, and located in the space intermediate the lateral parts 6 and 7 of said extension strips, as illustrated 105 in Figs. 1 and 2, thereby slidably connecting the extension strips. The lateral parts of the extension strips are spaced sufficiently to permit of play of the loop between the adjacent edges of the lateral parts, whereby the 110

hand may be easily accommodated under the extension strips, that is when the hand assumes the shape, as shown in Fig. 1 while holding a pen or pencil. The body of the blotter may be made long enough to the rear of the extension strips 4 and 5, that is, if desired, so as to extend approximately to the rear of the palm of the hand or the heel thereof. In using the blotter, every now and then after writing a line or a section thereof, the hand may be partly straightened out and moved forwardly over the writing and the blotter applied, or the hand partly turned, so that the side of the hand adjacent the little finger may apply pressure on the blotter.

The invention having been set forth what is claimed as new and useful is:—

1. A blotter for the hand, comprising in combination with a body, lateral extension strips forming integral parts with the longitudinal side edges of the body and adapted to overlap each other adjacent the back of the hand, a loop encircling the overlapped

ends of the extension strips slidably uniting the same, and means on the ends of the extension strips coöoperating with the loop to prevent slidable disconnection of the strips. 25

2. A blotter for the hand, comprising in combination with a body, lateral extension strips forming integral parts with the longitudinal side edges of the body and adapted to overlap each other adjacent the back of the hand, the extremities of the overlapped strips having transverse parts extending laterally from the opposite edges of the strips and being spaced, and a loop encircling the extension strips between the spaced transverse parts of the strips, thereby slidably disconnectedly uniting the extension strips. 30 35 40

In testimony whereof I have signed my name to this specification in the presence of two subscribing witnesses.

STEPHEN HUDACK.
